UNITED STATES PATENT OFFICE

161,873

GUM MASSAGER

Charles L. Rosengard, Hartford, Conn.

Application January 5, 1950, Serial No. 7,014

Term of patent 14 years

(Cl. D83—1)

To all whom it may concern:

Be it known that I, Charles L. Rosengard, a citizen of the United States, residing at Hartford, in the county of Hartford and State of Connecticut, have invented a new, original, and ornamental Design for Gum Massager, of which the following is a specification, reference being had to the accompanying drawing, forming part thereof.

Fig. 1 is a plan view of a gum massager embodying my new design.

Fig. 2 is an elevational front view thereof.

Fig. 3 is an elevational side view thereof.

Fig. 4 is a fragmentary rear view illustrating the head portion of my gum massager.

I claim:

The ornamental design for a gum massager, substantially as shown.

CHARLES L. ROSENGARD.
